ELECTRIC SWITCH

Filed Nov. 6, 1928

UNITED STATES PATENT OFFICE

EVERETT CHAPMAN, OF CLEVELAND, OHIO, ASSIGNOR TO THE LINCOLN ELECTRIC COMPANY, OF CLEVELAND, OHIO, A CORPORATION OF OHIO

ELECTRIC SWITCH

Application filed November 6, 1930. Serial No. 317,034.

The present invention, relating, as indicated, to electric switches has more particular reference to switches of the type having a plurality of contact actuators, and its primary object, broadly stated, is to provide an improved switch for use in motor controlling and similar circuits.

More specifically, my invention contemplates providing, in a motor controlling or like switch, a starting contact actuator and a stopping contact actuator, the former (in a preferred embodiment) taking the form of a push button arranged for effecting the desired connections, and the latter consisting of a concentrically disposed push piece having a part extending beyond or above the top of such push button. This relative arrangement of the starting and stopping contact actuators not only makes for their ready distinguishability, especially under different conditions of illumination, but it also provides for the more easy and convenient operation of the stopping as compared with the starting actuator, because the position and shape of the former are such as to permit of its manipulation with most any part of the hand, whereas a single finger must be used when depressing the latter. By way of further increasing the usefulness of a switch of the type just described, my invention provides a color scheme which either alone or in association with suitable indicia on the starting button greatly improves the distinguishability of the two actuators, such scheme contemplating the use of a green color for the starting actuator, a red color for the stopping actuator and a comparatively darker and contrasting color, such as black, for the top plate which surrounds and positions the actuators. Also for use in connection with this actuator arrangement, my invention further provides improved stationary and movable contact mechanism and mountings which are of such construction as to not only insure positive and certain operation but to also materially reduce the cost of manufacturing and assembling the individual parts.

To the accomplishment of the foregoing and related ends, said invention, then, con-

sists of the means hereinafter fully described and particularly pointed out in the claims; the annexed drawing and the following description setting forth in detail certain structure embodying the invention, such disclosed means constituting, however, but one of various mechanical forms in which the principle of the invention may be used.

In said annexed drawing:

Fig. 1 is a perspective view of a switch embodying the present improvements; Fig. 2 is a plan view of the switch shown in Fig. 1; Fig. 3 is a vertical section which was taken along the line 3—3 of Fig. 2; Fig. 4 is a vertical section which was taken along the line 4—4 of Fig. 2; Fig. 5 is a plan view of the inner unit of the switch shown in preceding figures; and Fig. 6 is a bottom plan view of the unit illustrated in Fig. 5.

By way of example, an embodiment of my invention is here shown in association with an outer casing 10 which consists of a bottom wall 11, opposite side walls 12 and 13 and an inturned top flange 14. The upper part of one of the side walls 13 may be inclined in the manner shown and its lower part is provided with a conduit inlet 15. Within the casing 10 and secured to an insulating top plate 16 by means of the screws 17 is an insulating mounting 18 which is arranged for carrying the contacts and their actuating members in the manner hereinafter explained. Such plate 16 is secured to the flange 14 by the screws 19 and has a centrally disposed opening 20 through which the contact actuating members 21 and 22 project. The inner of these contact actuators is here shown as a push button which is fixedly mounted upon the upper end of a shaft 23, such shaft being reciprocably mounted in a boss 24 and carrying on its lower end a slightly loose contact disc 25. Between the lower face of the button 21 and the upper face of the boss 24 is a helical compression spring 26, this spring encircling the shaft 23 and acting to hold such button in its raised or inoperative position and the disc 25 out of engagement with the contacts 27 and 28. The outer of the contact actuators above referred to consists of an annular shaped push piece

which has a central bore 29 for fitting over and guiding the push button 21, an outer surface 30 for fitting within the cover opening 20, and a lower enlargement 31 for slidably coacting with the inner surface 32 of the mounting 18. To the top of the shoulder between the enlargement 31 and the surface 30 is secured a contact ring 33, and between the underside of such enlargement and a concave seat 34 which surrounds the boss 24 is a compression spring 35, this spring functioning to hold the push piece 22 in its elevated position and the ring 33 in engagement with the contacts 36 and 37. These contacts, the plate 38, and the plate 39 are firmly held against the opposite ends of the mounting 18 by means of the tie screws 40. Another plate 41 is held in the position indicated in Fig. 6 by a screw 42, and each of such plates has a wire attaching screw 43 for making the usual connections with the conductors of a motor starting or like circuit, such conductors as above stated passing into the casing 10 through the opening 15.

It will be understood that the fixed contacts 36, 37, 27, and 28 are connected in such a manner that the downward movement of the push button 21 will be effective to start the motor in the circuit by electrically connecting the latter two of such contacts, and that the downward movement of the push piece 22 will be effective to stop such motor by electrically disconnecting the former two of such contacts. The inner contact actuator 21 is desirably although not necessarily formed of a green insulating material such as bakelite, and the outer contact actuator 22 may be formed of a similar material colored red. The top plate 16 is also formed of insulating material and if desired it may be colored black or given some other dark color in order to form a contrasting background for the contact actuators. This color scheme has the effect of making such actuators clearly visible and easily distinguishable in the light, and their relative arrangement materially contributes to their distinguishability in the dark. Furthermore, it will be noted that the top of the push piece 22 extends above the top of the push button 21 and that the former is disposed in concentric relation to the latter. It is thus apparent that in starting the motor, the operator must deliberately insert his finger into the cup-like surrounding part of the push piece 22 in order to depress the button 21, and that in stopping such motor, any part of the hand can be used for depressing the push piece 22. In other words, the starting of a motor by means of my improved switch requires that the operator give specific attention to the starting operation, and this in turn has a tendency to induce a mental review of the situation which may lead to the discovery of something which would cause damage in case the motor was started. On

the other hand, the stopping contact actuator is so positioned that such motor may be quickly stopped in the event of an emergency; it only being necessary to depress the annular push piece 22, an operation which can be readily effected because the relatively more accessible position of such push piece as compared with that of the starting button 21.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:—

1. In an electric safety switching device having a plurality of movable contacts, the combination of a hollow member for actuating one of such contacts, and means terminating in a relatively inaccessible position within said hollow member for actuating another of said contacts.

2. In an electric safety switching device having a plurality of movable contacts, the combination of a hollow member for actuating one of said contacts, and a push button terminating in a relatively inaccessible position within said hollow member for actuating another of said contacts.

3. In an electric safety switching device having a plurality of movable contacts, the combination of a tubular member for actuating one of said contacts, said member having a cup shaped end, and a push button terminating in a relatively inaccessible position within said cup shaped end for actuating another of said contacts.

4. In an electric safety switching device having a plurality of movable contacts, the combination of a resiliently supported hollow member for actuating one of said contacts, and a resiliently supported member terminating in a relatively inaccessible position within said hollow member for actuating another of said contacts.

5. In an electric safety switching device, the combination of a plurality of fixed contacts, a plurality of movable contacts for engagement with said fixed contacts, a hollow member normally maintaining one of said movable contacts in engagement with some of said fixed contacts, and means terminating in a relatively inaccessible position within said hollow member normally maintaining another of said movable contacts out of engagement with some of said fixed contacts.

6. In an electric safety switching device, the combination of a plurality of fixed contacts, a plurality of movable contacts for engagement with said fixed contacts, a resiliently supported tubular member normally maintaining one of said movable contacts in engagement with some of said fixed contacts,

and a resiliently supported push button terminating in a relatively inaccessible position within said tubular member and normally maintaining one of said movable contacts out of engagement with some of said fixed contacts.

5 7. In an electric safety switching device, the combination of a movable contact actuator with its one terminal in the form of a 10 cup, and a movable contact actuator in the form of a button in a relatively inaccessible position within such cup.

Signed by me, this 5th day of November, 1928.
